WIRE STRETCHERS

John Valenta, Kitchener, Ontario, Canada

Application May 12, 1952, Serial No. 287,444

1 Claim. (Cl. 140—123.6)

This invention relates to apparatus for tensioning or tightening tie wires such as used for holding in proper relationship the parts of the forms used to receive concrete in constructing concrete walls, and also for tensioning and tying binding or reinforcing wires used to encircle packing cases, crates or other structures.

Usually the application, tensioning and tying of such wires has involved the use of a plurality of separate tools and the object of the present invention is to devise a tool which will include and combine in a convenient arrangement all the parts necessary for the carrying out successfully by one person and with a minimum of trouble all the steps involved in the wiring of such wall forms or other structures. These operations include the preliminary tightening up of the wire, the severing of the wire from the roll, and the final tightening of the tie wire by twisting together the ends thereof.

A further object is to devise a tool which is comparatively inexpensive, of sufficiently light weight to enable it to be handled easily, and also sufficiently small to be used in restricted space.

These and other objects which will hereinafter appear are attained by means of the constructions hereinafter described and illustrated in the accompanying drawings in which

Fig. 1 is a front elevation of the improved tool;

Fig. 2 is a side view of the same;

Fig. 3 is a plan view of the work-engaging member;

Fig. 4 is a vertical section of the upper part of the tool;

Fig. 5 is a perspective view of the upper part of the tool;

Fig. 6 is a side view of part of the tool showing the wire pulling means;

Fig. 7 is a perspective view of part of the wire-pulling means;

Fig. 8 is a perspective detail of part of the wire-pulling means;

Fig. 9 is a plan view showing the tool used in conjunction with a form for molding a concrete wall;

Fig. 10 is a similar view showing the tool used for applying a binding or reinforcing wire around a box or other structure; and

Fig. 11 is a perspective view of the wire cutter.

In the drawings like numerals of reference indicate corresponding parts in the different figures.

In Fig. 9 the tool is shown as used for tightening and tying a reinforcing or tie wire for a form into which concrete for a wall is to be poured. 1 indicates the facing boards and 2 the upright posts. A wire 3 usually extends across the gap between the facing boards, through or between the spacing boards and passed around the posts, and the ends of the wire tied together. It is important that the facing boards be uniformly spaced apart, and spacer bars are usually provided for this purpose.

It is also important that the form be firmly held against spreading apart during the filling of the form, and the purpose of the wires 3 is to prevent this spreading. It

2

is important therefore that the wires should be drawn up or tensioned sufficiently tightly to hold the parts of the form in proper relationship.

The tool comprises a shank 4. At opposite sides of this shank are positioned the arms 5 and 6. The shank 4 and arms 5 and 6 are secured together by a screw 8, and a hand grip 7 is secured at each side of the shank. The arms 5 and 6 within the handle are each shaped to provide a fulcrum 9a on which the arm may rock. The upper ends of the arms, as a result of this construction, normally tend to lie away from the shank. The upper ends of the arms are provided with inwardly directed clamping jaws 9 and 10, the ends of which are knurled or otherwise roughened or toothed to provide a good gripping surface. The corresponding portions of the shank 4 opposite the ends of the jaws are also knurled or otherwise roughened as shown.

Extending through the shank 4 and arms 5 and 6 is a threaded rod 11, and on the outer ends of this rod are threaded clamping nuts 12 and 13. This threaded rod is held from rotation by a pin 27. By screwing these clamping nuts towards the arms, the latter are moved to force the jaws 9 and 10 towards the shank 4.

The shank 4 has a head on its upper end, which includes a fixed disk 15 and a work-engaging member 14 rotatably mounted on the disk. The work-engaging member 14 is provided with a ferrule 16 thereon provided with an inwardly directed flange which underlies the disk 15.

The disk is provided with two holes 18 for the passage of the wire, while the work-engaging member 14 is provided with a central cavity or recess 17 in which the twisting of the portions of the wire above the holes 18 may be effected. The work-engaging member 14 is provided with a comparatively deep V-shaped groove 19 extending across its face, and also a smaller groove 20 arranged at right angles thereto.

Rotatable in a socket formed in a shoulder 21 formed on the side of the shank 4 is a wire cutter 22, the projecting end of which is shaped to form a cutting edge 23. This cutter is shown more particularly in Fig. 11. At its other end the cutter has a lever arm 24 thereon by means of which it may be rocked. On the side of the shank 4 is secured a slotted quadrant 25, into the slot of which extends a pin 26 on the side of the lever arm 24, which thus limits the extent of movement of said lever arm and therefore also the movement of the cutter 22.

On a support 28 secured to the side of the shank 4 above the handle 7 is pivoted at 37 a wire pulling device, which comprises a lever member 29 on which is pivoted a second lever member 30. The lever member 29 is provided with a gripping post 31, which is provided with a recess 32 in its side. The other lever member 30 is provided with a post 31a, which extends through a slot 36 in the lever member 29 and is provided with a laterally extending projection 33 which is adapted to extend into the recess 32 to clamp the wire 34, which is indicated in full lines in Fig. 6 and in dotted lines in Fig. 7.

The wire 34, drawn from a roll 35, is threaded upwardly between the jaw 10 and shank 4, through one of the holes 18 in the disk 15, passed around the work or form as indicated in Fig. 9, then threaded back through the other hole 18 in the disk 15 and between the jaw 9 and shank 4. The clamping nut 12 is tightened up to clamp the wire between the jaw 9 and shank 4 so that the end of the wire cannot be drawn back. The wire puller is then engaged with the wire leading from the roll by gripping the wire between the gripping projection 33 and the bottom of the recess 32. By rocking the wire puller as a whole on the pivot 37, any slack wire is drawn back. If one operation of the wire puller is not enough, one or more fresh grips may be taken further up on the wire

as indicated in dotted lines in Fig. 6, and the puller again rocked to effect any necessary tightening.

As soon as the wire about the work or structure being bound is drawn sufficiently tight, it may be held tight by turning down the clamping nut 13 to cause the jaw 10 to clamp the wire against the shank 4.

By rocking the lever arm 24, the wire is severed by the cutting edge 23 on the cutter 22. The tool is then rotated relative to the work-engaging member 14, which latter is held from rotation by the engagement of the corner of the upright 2 in the groove 19 as indicated in Fig. 9, and the portions of the wire in the cavity or recess 17 are twisted on one another to complete the tightening of the wire and, at the same time secure the ends together.

When the ends of the wire are twisted together, the clamping nuts 12 and 13 are loosened up to allow the jaws 9 and 10 to release the wire ends and permit the withdrawal of the tool therefrom.

While the tool is of particular advantage for wiring together concrete forms, it is also useful for applying binding wire about packing cases or other structures. In Fig. 10 the tool is shown as used in applying a binding wire about a rectangular structure 38. The tool is used in substantially the same way as above described. The work-engaging member 14 of the head is held from rotation during the twisting operation by engaging the structure-encircling wire in the groove 20.

What is claimed is:

A wire stretching tool comprising a main supporting

shank having a forward end and a rear end, the forward end provided with two generally parallel side faces oppositely disposed with respect to the longitudinal axis of the shank, a hand grip on the rear end of the shank, a work engaging head rotatably supported on the forward end of the shank to turn about the longitudinal axis thereof, said head being centrally apertured to provide a passageway for wire and being open to said side faces, a pair of wire engaging clamps, each including a jaw integral with an arm capable of flexing, said arm extending alongside of the shank toward the rear end thereof, said arm being fulcrumed on the shank near its rear end and being secured to the shank under tension rearwardly of the fulcrum, a rod transversely extending from the shank and freely passing through the distal end of the shank, and a knob screwed on the outer end of the rod and bearing on the arm for screw adjustment to close the jaw.
